UNITED STATES PATENT OFFICE.

GEORGE M. STEDMAN, OF AURORA, INDIANA.

VIBRATING SCREEN.

Application filed March 27, 1925. Serial No. 18,858.

My invention relates to a vibratory screen, for screening granular materials.

One of the objects of the invention is to provide a vibratory mechanism which can be 5 compactly arranged and housed to keep the controlling cam constantly lubricated and protected from the atmosphere of fine dust and suspended abrasive particles.

Another object of the invention is to provide 10 a simple and efficient species of vibratory elements particularly designed to produce an action wherein the screen is gradually raised to its maximum vertical position and then suddenly dropped or snapped back to the lowest position with a jolt or impact, this gravity-drop action being preferably accentuated by coordinating therewith a resilient screen-agitating instrumentality.

Another object of the invention is to provide 20 a vibrating yoke superposed in relation to the screen enabling the power shaft and its cam or tappet rotary member to be supported in relation to the bridge member of the yoke, the lower end of the yoke extending 25 to the plane of the screen and engaging a resilient agitator disposed along the medial line of the under surface of the screen. Preferably also I provide a spring pressed 30 lever of the compression or tension type of spring for engaging said agitator to normally hold the medial portion in depressed position.

Another object of the invention is to so 35 yieldingly attach the screen margins to the side members of the supporting frame that the screen will have a unitary flexation in a plane transverse to the plane of the tappet or agitating action.

This marginal spring support for the 40 screen has the additional advantage of providing security in the nature of a clamp or grip upon the marginal portion of the screen which will prevent rupture of the screen when stressed by the tappet or vibratory action, and which will also constitute a 45 convenient means for attaching and detaching or adjusting the screen.

I am aware that this tappet order of vibratory screen is not broadly new, many 50 forms differing from mine having been heretofore employed, for instance, such a construction as is exemplified in the Leahy Patent No. 1,456,067, of May 22nd, 1923, in 55 which the tappet engages the upper screen

surface and is acted upon to cause the slow depression of the screen and the quick raising of it with a snap or abrupt spring return to maximum vertical position.

The problem of the vibrating screen for 60 the treatment of granular material is largely to protect the operative parts from the abrasive dust and at the same time afford adequate lubrication. When the actuating mechanism which is exposed to this dust is 65 lubricated, the dust or abrasive particles working into the lubricant make a grinding action which rapidly wears the operative parts.

I have been able to effectually solve this 70 problem and to overcome this difficulty in a very satisfactory manner by the provision of the superposed vibratory yoke herein disclosed, providing as it does for the complete protection and lubrication of the operative 75 mechanism.

Other features and certain advantages will be more fully set forth in the description of the accompanying drawings forming a part 80 of this specification, in which:

Figure 1 is a plan view of the screen.

Figure 2 is a side view thereof.

Figure 3 is an enlarged sectional view on line 3—3 of Figure 1.

Figure 4 is an enlarged sectional view on line 4—4 of Figure 1, showing the mechanism for vibrating the screen.

Figure 5 is a detailed sectional view on line 5—5 of Figure 1.

The shape of the frame is immaterial, but 90 I have shown for my purpose a rectangular marginal frame or bed 1, preferably disposed approximately in horizontal plane although it may be tilted if desired. In this frame is secured the screen 2, the detail securing 95 members being shown in Figure 3, as comprising a spring plunger or pin 3 passing through the side frame pieces, the coil spring 4 being interposed between the exterior of the frame piece and the bolt nuts 5. On 100 the other end of the pin 3 within the frame is the bracket 6. The margins of the screen are held between the uneven surfaces of the bottom clamping block 7 and top clamping block 8, the uneven surfaces being of irregular or grip formation. These blocks 7, 8, with the screen gripped between these surfaces, are held as a unit upon the brackets 6 and the spring plungers 3 by means of 105 bolts 9. These blocks are preferably of 110

wood or compressible material which will not too harshly impinge upon the screen and these blocks and spring plungers are distributed adjacent one another upon opposite sides of the frame as shown in Figure 1.

From this construction it will be seen that when the medial portion of the screen is depressed, the opposite margins of the screen move toward one another, so that 10 when the spring is vibrated in the plane of the tappet action there is a constant and corresponding movement of the screen in the transverse plane permitted by this 15 spring plunger method of supporting the opposite margins of the screen in relation to this frame.

The vibrating yoke consists of a U-shaped frame superposed in relation to the main frame and comprising a link 10 and bridge 20 11 disposed in the medial longitudinal line of the screen. The bridge member 11 of the yoke has a centrally disposed bearing plate 18 for engagement with the rotary member or cam wheel 16. Each link of the yoke has 25 a depending bracket 17 extending to the plane of the screen. The brackets 17 are preferably pivotally connected to or suspended from the lower ends of the yoke links. Strictly speaking, the brackets are 30 supported upon the agitator which extends under the screen and the yoke is supported upon and by the brackets. In the central longitudinal line of the frame and below the screen is a resilient agitating member 19, 35 approximating bow-like contours as it is preferably formed of resilient wood intended to vibrate at the middle portion which is attached to brackets 17, its opposite ends being secured to the end portions of the 40 frame. This resilient agitator 19 is connected or operatively engages the under surface of the screen so that it moves, or at least the medial portion of it moves unitarily with the yoke. This resilient agitator 19 is 45 preferably held normally in its depressed position under spring tension administered through a lever 20 intermediately fulcrumed, the inner end 21 of which is connected to the member 19, and the outer end 50 of which is under pressure by the spring 21^a (see Figure 2), this spring pressing the outer end of the lever normally upward and therefore urging the inner end of the lever 55 normally downward. Superposed transversely and medially upon frame 1 is a second frame 30 comprising end brackets 12 and cross beams 13 and a cross head 14 carrying the lubricating trough and providing bearings 15 for the drive shaft 25.

60 The cross head 14 (see Figure 4) carries at its medial portion the housing or lubricating trough 24 through which extends the driving shaft 25 supported in suitable bearings 15 on the cross head 14. On the housed portion of this driving shaft is placed the

cam wheel or rotary member 16 having its periphery formed cam-like to engage the bearing plate 18, the cam surface being characterized by the abrupt shoulder 27 which in the direction of rotation shown in 70 Figure 4, slowly raises the yoke to a maximum vertical position at the time the shoulder 27 engages the bearing plate 18, and as this shoulder leaves the bearing plate the entire yoke drops bodily and abruptly under the combined influence of gravity and the spring pressure of the lever 20.

By the construction of the oil trough 24 for the cam wheel 16, I am able to keep a constant supply of lubricant therein and I 80 also preferably employ as closures the bracket plates 28 adjacent the opposite sides of the bearing plate 18 which completely house in this portion of the shaft and the operating cam. The yoke links have vertical guides 29 in relation to the cross-head. 85

Owing to the complete lubrication of this device and its protection from abrasive dust, as well as owing to the superposed relationship of the cam and driving shaft 90 and also very largely because of the spring or resilient connection between the underside of the yoke and the under surface of the screen, the screen being in turn spring-attached to the margins of the frame in a 95 plane transverse to the tappet or vibratory action, it is possible to very materially speed up the operation of the driving shaft and the cam to give a high rapidity vibratory action to the parts characterized by the 100 relatively slow rising motion of the medial zone of the screen and its sharp return. This action on the abrasive material is very much like tossing in the air or dropping the screen or bottom from under it quickly so 105 that the abrasive material is suspended and drops with an impact upon the screen in its lowermost position. The screening operation is not only improved or rendered more efficient by this particular action but the result is materially improved and the separation action quickened by this organization which permits a relatively high speed 110 of vibration made possible where the parts are sufficiently lubricated and protected and where there are no rupturing stresses upon the screen itself, due to the fact that the vibratory action is of a spring nature and the spring influence is exerted in these 115 transverse planes. Also this method of supporting and operating the screen preserves the life and efficiency of the screen. 120

125 Preferably I provide the adjustable stops 31 in the cross head and placed under the middle of the yoke which may be set to limit the length of the drop to less dimension than the drop provided by the height of the shoulder 27. Various means may be provided for rotating the yoke and for connecting it to the medial zone of the screen 130

without departing from the principles disclosed in the particular embodiment of the illustration.

Having described my invention, I claim:

- 5 1. In combination with a marginal frame and a screen to be vibrated, a superposed yoke having a member medially bridging the frame, formed with a medial bearing plate and with depending brackets, a resilient agitator connected to said brackets and engaging a medial portion of the under-surface of the screen, a power shaft passing through the yoke and under its bridge member, and a rotary member on the shaft having an irregular periphery engaging the plate for vibrating the yoke, agitator and screen.
- 10 2. In combination with a marginal frame and screen to be vibrated, a superposed yoke having a member medially bridging the frame and formed with a centrally positioned bearing plate, a resilient agitator below the screen, the ends of which are secured to the frame, the medial portion of said agitator being connected to the lower ends of the yoke, a power shaft passing through the yoke and under the bridge member, and a rotary member on the shaft having an irregular periphery engaging the said bearing plate of the yoke.
- 15 3. In combination with a marginal frame and screen to be vibrated, a superposed yoke having a member bridging the frame and formed with a medially positioned bearing plate, brackets depending from the ends of said yoke, a resilient agitator below the screen, the ends of which are secured to the frame, means connecting the medial portion of said agitator with said brackets depending from said yoke, a power shaft passing through the yoke and under the bridge member, a rotary member on the shaft having an irregular periphery engaging the said bearing plate of the yoke, and a lubrication trough member suspended adjacent the medial portion of said yoke and forming a housing in which the said rotary member operates.
- 20 4. In combination with a marginal frame and screen to be vibrated, a superposed yoke having a member medially bridging the frame transversely and formed with a medially positioned bearing plate, brackets depending from the said yoke, a resilient agitator below the screen, the ends of which are secured to the frame, means connecting the medial portion of said agitator with said brackets, a power shaft passing through the yoke and under the bridge member, a rotary member on the shaft having an irregular periphery engaging the said bearing plate of the yoke, a suspended lubricating trough for the under periphery of said rotary member, and a spring actuated lever supported by the main frame and having one end engaging the medial portion of said spring actuating

ator for normally depressing the medial zone of the screen.

5. In combination with a marginal frame and a screen to be vibrated, a stationary cross member medially bridging the frame, a superposed yoke having a member transversely bridging the cross member, formed with a medial bearing plate and with brackets, a resilient screen agitator supported at its ends by said frame, said brackets engaging a medial portion of the agitator, said agitator extending in the plane of the yoke, a power shaft passing transversely through the yoke and under its bridge member, a rotary member on the shaft having an irregular periphery engaging the yoke plate for vibrating the agitator and screen, adjustable stops on the stationary cross member below said bridging member of the yoke for engaging the underside of the yoke for controlling the vibratory movement of said yoke, and means for connecting the opposite margins of the screen to the corresponding side pieces of the frame consisting of spring controlled members permitting the opposite margins of the spring to vibrate in a plane transverse to the movement of the yoke.

6. In combination with a marginal frame and a screen to be vibrated, means yieldingly securing the opposite margins of the screen to the opposite side pieces of said frame, a stationary cross member medially bridging said frame, a yoke superposed in a transverse relation to the stationary cross member, means connecting the lower extremities of the yoke to the medial zone of the screen, a shaft extending medially and longitudinally below the superposed portion of the yoke, a cam on the shaft for engaging the underside of the yoke for vibrating the same, and adjustable stops on the stationary cross member for engaging the yoke for controlling the vibratory movement of said yoke and resilient member.

7. In a device of the class described, in combination with a main frame, a screen to be vibrated, means for yieldingly attaching the opposite margins of the spring to the opposite side pieces of said frame, a resilient agitator, the ends of which are secured to the end pieces of the frame below the screen, the medial portion of said agitator being operatively engaged with the under-surface of the screen, a spring mechanism supported on the frame holding the medial portion of said agitator in depressed position, and a vibratory mechanism positioned above the screen and operatively connected to the medial portion of said vibrating member below the screen.

8. In a device of the class described, in combination with a main frame, a screen to be vibrated, means for yieldingly attaching the opposite margins of the spring to

the opposite side pieces of said frame, a resilient agitator, the ends of which are secured to the end pieces of the frame below the screen, the medial portion of said agitator

5 being operatively engaged with the under-surface of the screen, a spring mechanism supported on the frame holding the medial portion of said agitator in depressed position, a vibratory mechanism positioned 10 above the screen and operatively connected to the medial portion of said vibrating member below the screen, said superposed vibratory mechanism comprising a power shaft and a cam wheel thereon, and means constituting a housing and lubricating trough 15 in which said wheel operates.

9. In a device of the class described, a marginal frame and a screen to be vibrated, the opposite margins of said screen being 20 yieldingly attached to opposite side pieces of the frame, a vibratory yoke superposed over the medial portion of the screen having a bearing plate, a shaft and cam wheel above the screen passing through the yoke, means 25 forming an oil trough and housing within which said cam operates, said cam engaging said bearing plate and being in the form of an abrupt shoulder to drop the yoke bodily, brackets depending from said yoke, a resilient agitator below the screen and engaging 30 the medial portion thereof, means connecting the medial portion of said agitator to the depending yoke brackets, and spring actuated means engaging the main frame 35 co-acting to hold said vibrating resilient actuator in its depressed position.

10. In a device of the class described, a main frame, a screen to be vibrated, a resilient agitator extending medially and longitudinally of said frame and engaging said screen, a superposed yoke having a member medially bridging the frame and depending member secured to said resilient agitator, vibrating means under said yoke for shaking 45 the screen, and a lever fulcrumed on the frame beneath the resilient agitator, said lever having one end attached to said resil-

ient agitator and the other end spring activated, and said lever depressing the medial zone of the screen for increasing the vibration of the screen. 50

11. In a device of the class described, a main frame, a screen to be vibrated, a resilient agitator extending longitudinally of the frame and engaging the screen, a superposed yoke attached to said resilient agitator, a power shaft extending through said superposed yoke, a rotary member on said shaft having an irregular periphery engaging the under side of said yoke, and a spring actuated lever medially engaging said resilient agitator for depressing the screen and hastening the fall of the yoke as the rotating member is activated to increase the vibration of the screen. 55

12. In combination with a marginal frame and a screen to be vibrated, a superposed yoke medially and transversely bridging said frame and formed with members, depending below the plane of the screen, means resiliently connecting said depending yoke ends with the medial zone of the screen, a second frame placed on the main frame and extending medially and transversely thereto providing a cross-head extending under the bridging portion of said yoke, a power shaft journaled in bearings on said cross heads, a cam on said shaft engaging a bearing on the bridging portion of the yoke, and a lubricating trough for the cam wheel formed 75 in a portion of said cross head. 80

13. In a pulsating screen, a frame, a screen tautly sustained within the frame, a resilient bar extending medially of and beneath the screen and secured at its opposite ends to the frame and engaged with the screen, tension means for said bar having a lever connection therewith, and means for intermittently agitating said bar for forcibly setting up bar vibration and screen pulsation. 85

In witness whereof, I hereunto subscribe my name.

GEORGE M. STEDMAN.
